UNITED STATES PATENT OFFICE.

HARRY V. BROWN, OF OKLAHOMA, OKLAHOMA, ASSIGNOR, BY MESNE ASSIGNMENTS, OF ONE-HALF TO EUGENE A. BARNES, JR., OF OKLAHOMA, OKLAHOMA.

MACHINE FOR MAKING BRICK.

Application filed December 24, 1920. Serial No. 433,065.

To all whom it may concern:

Be it known that I, HARRY V. BROWN, a citizen of the United States, and a resident of Oklahoma city, in the county of Okla-

5 homa and State of Oklahoma, have invented certain Improvements in Machines for Making Brick, of which the following is a specification, reference being had to the accompanying drawings.

10 The invention pertains to machines for making concrete brick and blocks.

Machines of this class commonly include a mold supported in position to have the concrete delivered into it manually or by 15 a feeding machine.

After the concrete has been placed in the mold, it is necessary to tamp or firmly pack it in order that it may be removed as a finished brick and placed for drying; and 20 when brick with a special finish face is to be made it is necessary to first place in the mold a quality of concrete especially prepared and mixed for said finish.

25 After the mold is completely filled and tamped, the surplus concrete is stroked off with a straight-edge and the finished brick is removed.

In machines of this class heretofore used, 30 one person is employed to attend to the filling of the mold; another to stroke off the surplus concrete; and another to remove the finished brick; with the result that while the finished brick may be produced a little quicker by the combined efforts of 35 the several persons than by one alone they are waiting on each other a greater portion of their individual time and the number of brick produced is not in proper proportion to the number of persons employed.

40 An object, therefore, of the invention is to provide a machine whose output of brick will be greater in proportion to the number of persons employed in its operation.

Other objects and advantages of the invention will be set forth in the ensuing description.

Figure 1 of the drawings is a plan view of the improved machine.

Figure 2 is a similar view, but with certain molds and their supporting brackets 50 swung to different positions.

Figure 3 is an elevation view of the machine, with the parts in the position shown in Figure 2.

Figure 4 is a reproduction of a portion of Figure 3 on larger scale.

Figure 5 is a sectional view on the same scale as Figure 4 and taken on the line 5—5 of Figure 2.

Like characters of reference designate 60 like parts in all the figures.

In carrying out the objects stated, the inventor provides as many molds as there are operations to be carried out in properly filling a mold and removing the finished 65 brick, and arranges said molds so that they may be circulated along a predetermined path of movement.

With the machine arranged in this way, 70 one person may attend to the filling of the mold; another to the stroking of the mold; and another to removing the brick.

In arranging the several molds to circulate, a vertical center-post 10 is provided and set firmly in a suitable footing, for example in a cast-iron foot-plate 11 resting 75 on concrete 12 in the ground.

This center-post 10 is arranged as a vertical spindle and has a number of supporting brackets 13 pivotally embracing it as 80 shown.

Each of the brackets 13 of which there are three in this instance, is formed into a mold 14 at a convenient radial distance from the center-post 10, and while said brackets 85 and molds cannot pass each other in their movements around the center-post their movements are otherwise wholly independent of each other and are produced manually by and at the convenience of the persons 90 operating the machine.

To support the molds 14 and lock them against movement while being filled, a support is provided and located where each mold can pass over it.

In this instance this support includes an 95 arcuate rail 15 which is concentric to the center-post 10 and supported at its end by posts 16 and 17 set in the concrete 12.

These posts 16 and 17 are connected to the 100 foot-plate 11 by radial braces 18 and 19, respectively.

At the end of the rail on which a mold 14 approaches it, a leaf-spring finger 20 is bolted to its supporting post 16, the upper or free end of this finger extending up along the outer face of the rail and above said rail in position to engage a notch 21 in a locking bearing 22 on the outer end of each mold.

When a mold 14 is swung onto the rail 15, the sloping surface 23 of the bearing 22 swings the finger 20 outward to where it will fall into the notch 21 by its own elasticity, and the mold is thus releasably locked in position to be filled.

During the filling of the mold 14 and the tamping of its contents, the rail 15 bears the strain that would otherwise be brought onto its supporting bracket 13 and onto the center-post 10.

By manually releasing the locking engagement of the finger 20, the filled mold 14 may be advanced in the direction of the arrows 24.

To stroke the surplus concrete 25 from the filled mold 14, a stroking-bar 26 is supported in position to have the mold pass under it immediately upon leaving filling position; and in this instance said stroking-bar is adjustably bolted to an arm 27 which radiates from the center-post 10.

The arm 27 adjustably embraces the center-post 10, and is provided with a set-screw 28 to clamp in place thereon.

By drawing the filled mold 14 under the stroking-bar 26 the surplus contents 25 is scraped off and falls to the ground.

After passing under the stroking-bar 26, each mold 14 is moved along to the advance end of the rail 15 where the notch 21 in its locking bearing 22 is engaged by a second leaf-spring finger 29 bolted to the post 17.

The bottom 30 and advancing side wall 31 of each mold 14 are connected together integrally or in some other rigid manner as best shown in Figure 5, and at their angle they are hinged to the remaining portion of the mold by pins 32 which pass pivotally through 33.

This arrangement allows the bottom 30 to be swung upward and the wall 31 outward, and thereby facilitates the removal of the finished brick.

The swinging movement of the bottom 30 to unloading position is limited at the proper time by an arm 34 which is cast on its lower face and abuts the lower edge of the side wall 35 of the mold 14.

The wall 31 is provided with a handle 36 for swinging it and the bottom 30.

To aid in swinging the bottom 30 upward, a vertically-movable plunger 37 is provided, the upper end of this plunger fitting slidably through a bearing 38 bolted to the inside of the rail 15 and the lower end pivoted to a foot lever 39 which is fulcrumed to a bearing 40 on the radial brace 19.

During the time the molds 14 are being swung from unloading position around to position for refilling and tamping, they may be cleaned and adjusted and in fact partly filled before coming to regular filling position on the rail 15.

The molds 14 all move in the same horizontal plane, and except as held or limited by the locking means described or by their abutment with each other the molds can be freely moved along their circular path in either direction.

The following is claimed:—

1. In a machine for making brick, a pivot centre, mold supports pivoted to and radiating therefrom, molds on the free ends of said supports, a fixed stroking bar in the path of the molds and beneath which they pass, a locking bearing on each mold, and means automatically engaging the same after the mold passes the stroking bar.

2. In a brick making machine, a rotary mold, a locking bearing on the end thereof and having a notch, a spring finger for engagement with said notch, a second spring finger for engagement with said notch, and a stroking bar disposed between said fingers.

Witness my hand this 20th day of November, 1920.

HARRY V. BROWN.
